UNITED STATES PATENT OFFICE.

ALBERT G. PETERKIN, JR., OF BRYN MAWR, AND WILLIAM F. STROUD, JR., OF CYNWYD, AND RICHARD B. CHILLAS, JR., OF PHILADELPHIA, PENNSYLVANIA, ASSIGNORS TO THE ATLANTIC REFINING COMPANY, OF PHILADELPHIA, PENNSYLVANIA, A CORPORATION OF PENNSYLVANIA.

DISTILLATION OF OILS.

Application filed June 4, 1925. Serial No. 34,750.

Our invention relates to the distillation of oils and more particularly to a process of distilling mineral oils without substantial cracking.

5 In accordance with our invention, crude petroleum, petroleum distillate or residuum is rapidly heated to a temperature in excess of its usual or normal cracking temperature to vaporize a substantial portion of the oil, 10 the vapors being kept in contact with the liquid oil until the maximum temperature is reached, and the vapors are then separated from the liquid, and the liquid oil is immediately cooled to a temperature below the 15 cracking temperature, or to a temperature which with attendant conditions will prevent cracking.

More particularly in accordance with our invention the oil is heated while passing at 20 high velocity through a series of tubes enclosed in a suitable heating chamber, as in the well known pipe still, and the hot mixture of oil and vapor so produced is discharged into a chamber or vapor box from 25 which the unvaporized oil or bottoms are drawn off and the vapors pass to a condenser or series of condensers, and if desired there may be utilized in conjunction suitable fractionating equipment. The high velocity 30 through the heater passage serves to keep the oil in the heating zone for a minimum period of time, to produce turbulent flow, and to increase the rate of heat transfer to the oil.

35 Further in accordance with our invention the aforesaid cooling is preferably effected, in part, by a cooling medium such as steam or equivalent, preferably superheated, brought into direct contact with the oil and 40 vapor mixture, to vaporize an additional portion of the oil with consequent cooling of the residual oil due to abstraction therefrom of the necessary latent heat of vaporization. If desired, this cooling may be 45 effected, in part, by a cooling medium passed through suitable heat-transfer structure out of contact with the mixture.

Further to prevent cracking of the residual liquid oil, it is passed through a cooler 50 and to storage as soon as possible. The time interval before cooling is shortened by making the vapor box of the smallest size necessary to handle the volume of vapors, thus

minimizing the time of passage of the oil therethrough. 55

Further in accordance with our invention, by utilization of a process of the character aforesaid, there may be produced asphalt having desirable characteristics from crude oils which heretofore have been considered 60 unsuitable for the production of this material.

In the commonly used methods of distilling petroleum oils, the oil is raised to a temperature of about 600° to 675° F. Such desired fractions as fail to distill over at this temperature are carried over by use of steam which is forced through or otherwise brought into contact with the oil. The temperature used is limited by the fact that petroleum oils above this temperature tend 65 to decompose or "crack" with the formation of lower boiling point hydrocarbons. The low temperature makes necessary the use of large amounts of steam, the proportion of 70 which increases with the boiling point and viscosity of the distillate fraction so as ultimately to render the distillation of oils above certain boiling points or viscosities 75 uneconomical. On account of this fact high boiling oils of high viscosity such as cylinder oils are not distilled but leave the distillation process as still bottoms, from which 80 must be separated by chemical or other means the asphaltic or other substantially 85 non-volatile substances. Some of the disadvantages of the process may be overcome 90 by conducting the distillation under sub-atmospheric pressures, whereby the boiling points of the oils are depressed. Even with 95 this improvement, however, the distillation is still slow and cumbersome.

Our method is contrasted with the commonly used methods referred to, in that the oil is heated with extreme rapidity in a 95 continuous stream while maintained in contact with the evolved vapors. It is further contrasted with common methods of operating pipe stills at such comparatively low temperatures as 600° to 700° F., in that the 100 oil in our process is heated to a temperature of the order of 750° F. which is considerably in excess of the normal cracking temperature. It is further contrasted with the process of cracking in a tube or pipe still 105 in that the oil is maintained at the high

- temperature for a very short period of time and, after separation of vapors, is immediately cooled before appreciable cracking can take place. Cracking of the vapors does not occur as they do not attain a sufficiently elevated temperature and cracking of the residual liquid oil does not occur since the period of time during which it is maintained above the cracking temperature is too short to allow decomposition. The pressure upon the oil within the heating zone of the tubular heater is preferably such only as is required to force the oil at the desired velocity through the tube structure, and may be, at the entrance to the tube structure, of the order of 70 or 80 pounds per square inch, the pressure in the tube structure falling to substantially atmospheric pressure at its discharge into the vapor box, fractionating column or tower.
- For an understanding of our process and for an illustration of one of the various forms our apparatus may take, reference is made to the accompanying drawing, in which: H is an oil heater of any suitable type, comprising a series of tubes or pipes T disposed in the tube chamber A, whose lower end communicates with a stack or flue a and into whose upper end are discharged from the combustion chamber B the hot gases and products of combustion resulting from the burning of any suitable fuel, as, for example, oil or gas delivered to the burner b. The oil to be treated is delivered from storage through the pipe c to the pump P, which delivers it at suitable pressure to the inlet of the tube system T, through which it rises, counter-current to the descending hot gases, and is discharged through the pipe d into the chamber C, which, in the example illustrated, is a fractionating column or tower, whose lower portion is in effect a vapor box, and which is provided with the vertically spaced fractionating members D of any suitable type, such, for example, as bubble plates, perforated plates, or equivalent. The oil discharge d into the chamber C is preferably disposed at a point one or more plates above the bottom. The oil charged through the pipe c may be cold or it may be preheated, as by absorption of heat in any one or more of the oil or vapor cooling structures hereinafter described, and is raised in temperature within the tube or pipe system T to a temperature in excess of cracking temperature, as, for example, of the order of 700 or 800° F. or higher, and passes through the tube structure at a velocity sufficiently high to shorten the period of traverse of the heating zone to an extent sufficient to inhibit substantial cracking. Vapors are liberated in the oil within the tube structure, and these, assisted by the velocity of the oil as delivered by the pump P, serve to effect turbu-

lence of the oil, thereby enhancing the rate of heat transfer to the oil. The pressure of the oil as delivered by the pump P is at least such as to maintain the desired velocity of the oil through the tube system, the magnitude of the pressure at the entrance into the tube system being determined principally by the length and cross section of the tubular passage.

With the bottom of the chamber C communicates the pipe e, through which is delivered steam, preferably previously superheated, as in a superheater E. Communicating with the bottom of the tower C is the pipe f, disposed preferably in the form of a trap g at suitable distance vertically below the pipe h, which delivers the bottoms through a cooler F to the storage tank S.

Connected with the upper end of the column C is the pipe i conducting vapors to the condenser G cooled by any suitable medium, as, for example, water, introduced at j and discharged at k. The condensate, comprising oil and water, is delivered through the pipe m, controlled by valve n, to the water separator I, in which the oil and water separate, the water passing off through the trapped pipe o. The oil passes off through the pipe p to the flow box J in which the oil is divided in any desired proportions into two streams, one of which passes off through the pipe q to the storage tank S⁵, and the other of which passes through the trapped pipe r into the upper end of the column C as a reflux stream which flows downwardly through the column countercurrent to the rising vapors.

In case the use of steam is not desired the water separator I may be cut out by closing valve n and the condensate from the condenser G passed directly from the pipe m through the valve s to the pipe p into the box J.

From suitable different altitudes within the column C may be withdrawn various desired fractions or cuts in liquid form through, for example, the several pipes t, u, v, w, delivering through associated coolers K¹, K², K³, K⁴, respectively, to the storage tanks S¹, S², S³ and S⁴, respectively.

The oil-vapor mixture entering the tower C at d comes into contact with the steam delivered through the pipe e, and is thereby immediately cooled to a temperature below the cracking temperature, or in any event, to a temperature which with the attendant conditions within the tower prevents cracking. The steam in the presence of the hot liquid oil causes part of the liquid oil to vaporize, and the vaporization so induced effects the cooling aforesaid by abstracting from the liquid oil the necessary latent heat of vaporization.

The unvaporized oil flows downwardly in the tower C, while in intimate contact with

the upwardly flowing steam, accumulating at the lower end thereof as bottoms, with resultant vaporization of lower boiling point components, and imparting to the bottoms 5 a higher flash test. The bottoms are continuously or at suitable intervals drawn off through the cooler F to the storage tank S.

The mixture of oil vapors and steam flows 10 upwardly through the tower, being brought in the course of its flow into intimate contact with the down flow of liquid through the tower and effecting the necessary interchange for fractionation. The liquid is drawn off as various fractions through pipes

15 t, u, v and w, the heavier fractions at the lower altitudes and the lighter fractions at the higher levels. The lightest vapors pass through the pipe i to the condenser G, the condensate eventually reaching the flow box

20 J, which divides the condensate stream, part passing through the pipe q to the storage tank S⁵ as aforesaid, and a suitable portion of the condensate being refluxed through the pipe r to the tower.

25 By means of our invention we are able, for example, to distill a mixed base mid-continent crude of an A. P. I. gravity of about 35.0° by raising it in the pipe still to a temperature of about 800° F. The oil 30 may be passed through at such a rate that its time of subjection to the heat of the furnace is about 2 to 10 minutes. The oil-vapor mixture on entering the tower may be brought into contact with steam in a proportion of 35 about 0.3 lb. per gallon of oil charged. Under these conditions the bottoms, to the extent of about 10% of the crude charged, drawn off at the base of the tower, represent a satisfactory asphalt, which product is not obtained 40 by the other well known methods of distilling such a crude. The character of the bottoms as well as of the distillate shows that no appreciable cracking has taken place in the distillation.

45 The production of satisfactory asphalt is a distinctive feature of our invention. In the ordinary methods of producing asphalt, whereby the crude oil is commonly reduced in a shell still to the desired physical characteristics, the crude oil must be of such character as to contain a considerable proportion of asphaltic bodies in order to give a satisfactory product. Such crude oils are commonly described as asphalt base crudes 50 and include in this broad classification crude oils such as the Mexican, Gulf Coast and the California crude oils. They are distinguished from those commonly known as mixed base crudes, of which the crude oils 55 of the Mid-Continent area are typical, by showing a higher content of asphaltic bodies as indicated by the so called carbon residue test which is described in detail in Bureau of Mines Bulletin #323-A, page 60 #79, and referred to in the appended claims

as "Bureau of Mines carbon residue test." Calculated back to the crude oil itself, typical carbon residue tests on crude oils of these two characters from well known fields are as follows:

Mixed base crudes.

	Per cent.
Powell	2.2
Haynesville	2.2
Rainbow Bend	1.5 75
Mexia	2.0
Wortham	1.6

Asphalt base crudes.

	Per cent.
Smackover	3.4 80
Panuco	10.0
Venezuela	4.8
California (Long Beach Field)	6.4

The above figures indicate a carbon residue 85 value of about 2.5% as a fair boundary between the mixed base and the asphalt base crudes. It has been general experience, as above stated, that the mixed base crudes under normal methods of operation do not 90 produce satisfactory asphalts. By our invention, however, we are able to produce even from this type of crude oil an asphalt which is equal in every respect to that produced from the high grade asphalt crudes, 95 such as Panuco, and is even somewhat superior in that it shows a higher flash test. In accordance with our invention there becomes available a novel residual asphalt having a penetration (Dow) above 140 and a flash 100 test (open cup) above 550° F. For any given penetration the corresponding flash test of our product is higher than in the case of asphalts produced by the methods heretofore commonly practiced.

105 For example, a satisfactory asphalt produced by our process from a 35.0° A. P. I. Gravity Mid-Continent crude oil shows a test as follows:

Per cent based on crude	9.34	110
Specific gravity	1.0225	
Flash ° F. (open cup)	595°	
Fire ° F. (open cup)	695°	
Penetration @ 77° F. (Dow)	153	
Melting point (B. & R.) ° F.	112°	115
Ductility (Dow)	110+	
Sol. in CS ₂	99.65%	
Fixed carbon	11.96%	
Ash	0.09%	
Engler viscosity at 300° F.	11.5 units.	120

While our invention has been described principally in its application to the distillation of crude petroleum, it is by no means limited to this material, but is equally applicable to the redistillation of the various distillates from petroleum, and other products which crack under normal distillation conditions. For example, in the distillation 125 of a crude petroleum as above described there 130

may be obtained a cut taken off from near the bottom of the tower, representing a distillate, too heavy for satisfactory pressing for removal of paraffin wax. Such a distillate is commonly redistilled with little or no steam giving a suitable "paraffin distillate" fraction and bottoms which are suitable only for fuel. This cut may be redistilled by our process with much better results in that clean, uncracked bottoms result which are suitable in every way for high grade cylinder stocks. The test below is characteristic of such bottoms by this process.

15 Gravity _____ 21.1° A. P. I.
 Viscosity @ 210° F. (Saybolt Universal) _____ 150
 Flash _____ 540° F.
 20 Fire _____ 635° F.

In the commonly used method the paraffine distillate is the only lubricating oil fraction and its viscosity is much lower than 25 that of the lubricating oil produced by our method.

In connection with the rerunning, by our process, of a heavy overhead such as the above, containing for example, a considerable percentage of oils with a Saybolt Universal viscosity of 100 seconds or above at 210° F., we have found it advantageous to add an amount of a naphtha fraction, boiling largely below 500° F. at atmospheric 35 pressure, in an amount of the order of 60% of the charge.

The addition of the naphtha makes use of the fact that the presence of the light boiling constituents has the effect of lowering 40 the boiling point of the high boiling oils. By its use distillation to a definite percentage bottoms may be accomplished at a much lower temperature than is necessary without it, and we are able to distill material which 45 otherwise could not be distilled without the use of excessive quantities of steam, as it would decompose before reaching its boiling point. At the same time, in the case of a pipe still, on account of the greater proportion 50 of vapor the linear rate of the flow through the tubes is increased, giving greater turbulence and shortening the time during which the oil must be maintained at a high temperature. These three factors combine to minimize cracking.

The cylinder stock obtained in this manner is superior to the cylinder stock obtained in the usual steam distillation, in that having been once distilled it is relatively free 60 from asphaltic bodies whereas in steam distillation the cylinder oil is a residue from the first distillation of the crude oil. As a result a smaller quantity of acid is required to treat our product than is required for a 65 cylinder stock obtained in the usual manner.

Also we are able to obtain these high viscosity distillates from coking crudes which ordinarily do not yield a cylinder stock due to the relatively large asphaltic content.

Our method of the character herein described may be practiced also in the treatment of paraffine base, naphthenic base and asphaltic base crude oils, particularly because of the higher rate of distillation possible. In the treatment of asphaltic base 75 crude oil, there will again be produced asphaltic bottoms having desirable characteristics; and in treating paraffine base oil there will be produced cylinder stock bottoms.

What we claim is:

1. The process of distilling petroleum or petroleum products without substantial cracking, which comprises rapidly heating the oil to a temperature in excess of 750 degrees F. by passing it at high velocity 85 through a zone in which heat is transferred thereto, maintaining the vapor in contact with the liquid oil while in the heating zone, immediately thereafter separating the vapor from the unvaporized oil, reducing the temperature of the unvaporized oil while out of contact with the separated vapor by a cooling medium to prevent cracking, and fractionating the separated vapor by immediately passing it countercurrent to a stream of 95 reflux oil.

2. The process of distilling petroleum or petroleum products without substantial cracking, which comprises rapidly heating the oil to a temperature in excess of 750 degrees F. without substantial cracking by 100 passing it at high velocity through a zone in which heat is transferred thereto, maintaining the vapor in contact with the liquid oil while in the heating zone, immediately thereafter separating the vapor from the unvaporized oil, cooling the unvaporized oil to prevent cracking by bringing it into contact with steam in a zone substantially devoid of the separated vapor, immediately 110 fractionating the vapor by passing it countercurrent to a stream of reflux liquid oil, and drawing off a portion of said reflux oil from contact with the vapor at an intermediate point in its course of travel. 115

3. The process of distilling petroleum or petroleum products without substantial cracking, which comprises rapidly heating the oil to a temperature in excess of 750 degrees F. by passing it at high velocity 120 through a zone in which heat is transferred thereto, maintaining the vapor in contact with the liquid oil while in the heating zone, immediately thereafter separating the vapor from the unvaporized oil, reducing the temperature of the unvaporized oil while out of contact with the separated vapor by a cooling medium to prevent cracking, immediately 125 fractionating the vapor by passing it countercurrent to a stream of reflux oil, 130

and drawing off a portion of said reflux oil from contact with the vapor at an intermediate point in its course of travel.

4. The process of producing asphalt from petroleum, which comprises rapidly heating oil containing asphaltic compounds to a temperature in excess of its normal cracking temperature, immediately separating the vapors from the liquid oil, then before substantial cracking occurs bringing the liquid oil into contact with steam, in a zone substantially devoid of the separated vapors, to effect reduction of temperature to prevent substantial cracking and to produce additional separation of non-asphaltic bodies to leave a residuum of asphalt.

5. The process of producing asphalt from crude petroleum containing asphaltic compounds in such quantity that the carbon residue is less than 2.5 per cent of the crude oil by Bureau of Mines carbon residue test, which comprises rapidly heating the oil to a temperature in excess of its normal cracking temperature, immediately separating the vapors from the liquid oil, and then before substantial cracking occurs cooling the asphaltic residuum by a cooling medium to prevent substantial cracking.

6. The process of producing asphalt from crude petroleum containing asphaltic compounds in such quantity that the carbon residue is less than 2.5 per cent of the crude oil by Bureau of Mines carbon residue test, which comprises rapidly heating the oil to a temperature in excess of its normal cracking temperature, immediately separating the vapors from the liquid oil, and immediately cooling the liquid oil by bringing it into contact with steam thereby effecting further vaporization of non-asphaltic bodies and effecting an asphaltic residuum.

7. The method of distilling hydrocarbon oils which comprises rapidly heating the oil to a temperature above its normal crack-

ing temperature, immediately thereafter separating from that portion of the oil which remains liquid the vapors which form as a result of the heating aforesaid, then before substantial cracking occurs passing the liquid oil into a zone substantially devoid of the separated vapors and bringing such oil into contact with steam to effect further vaporization and to effect cooling to prevent substantial cracking.

8. The method of distilling hydrocarbon oils which comprises rapidly applying heat to a continuous stream of oil to raise its temperature above that at which it will normally crack, immediately thereafter continuously separating from that portion of the oil which remains liquid the vapors which form as a result of the application of heat aforesaid, then before substantial cracking occurs continuously passing the liquid oil into a zone substantially devoid of the separated vapors and bringing such oil into contact with steam by passing it counter-current thereto to effect further vaporization and to cool the liquid oil to prevent substantial cracking.

9. The method of distilling hydrocarbon oils which comprises rapidly heating the oil to a temperature above its normal cracking temperature, maintaining the vapors which form as a result of the heating in contact with the liquid oil during application of heat thereto, immediately thereafter separating the vapors from the liquid oil, then before substantial cracking occurs passing the liquid oil into a zone substantially devoid of the separated vapors and bringing such oil into contact with steam to effect further vaporization and to effect cooling to prevent substantial cracking.
